UNITED STATES PATENT OFFICE.

JAMES SHERIDAN, OF FRANKLIN, PENNSYLVANIA.

MEANS FOR HANDLING PAVING BLOCKS OR BRICKS.

No. 888,662.

Specification of Letters Patent.

Patented May 26, 1908.

Application filed November 19, 1907. Serial No. 402,886.

To all whom it may concern:

Be it known that I, JAMES SHERIDAN, of Franklin, in the county of Venango and State of Pennsylvania, have invented certain new and useful Improvements in Means for Handling Paving Blocks or Bricks; and I do hereby declare the following to be a full, clear, and exact description of the invention, such as will enable others skilled in the art to 10 which it appertains to make and use the same.

My invention relates to improved means for handling paving bricks or blocks and more particularly to improvements upon 15 that for which Letters-Patent were granted to me on the 22nd. day of September 1896, and designated by Number 568,147.

One object of my present invention is to provide means whereby the blocks or bricks 20 can be effectually clamped within a carrying frame and quickly released therefrom when the frame and its contents are properly located on a road-bed.

A further object is to so construct the device that it can be readily utilized, not only for placing bricks or blocks in position on a road-bed, but also for conveying said blocks or bricks in proper arrangement for depositing in position on the road-bed, from a source 30 of supply.

A further object is to provide a holder for bricks or blocks to be placed upon the road-bed, having means for clamping the blocks or bricks both endwise and sidewise, and to 35 provide operating devices whereby all of the clamping means can be manipulated simultaneously or whereby the end clamping means can be operated without at the same time operating the side clamping means, as 40 desired.

A further object is to provide simple and efficient means for guiding the block or bricks from the carrying frame onto the road-bed.

45 A further object is to provide means whereby several superimposed tiers of blocks or bricks can be conveyed from a point of supply to a road-bed and deposited upon the latter, one tier at a time.

50 With these objects in view the invention consists in certain novel feature of construction and combinations and arrangements of parts as hereinafter set forth and pointed out in the claims.

55 In the accompanying drawings, Figure 1 is a plan view, partly in section, illustrating my

improvements. Fig. 2 is a side view with the supplemental frame or box in place. Fig. 3 is an end view. Fig. 4 is a longitudinal sectional view, and Fig. 5 is a transverse sectional view. Fig. 6 is a transverse sectional view showing blocks or bricks clamped in the device and ready to be deposited upon a roadway.

1 represents a base comprising parallel bars 2, 2, and a convex platform 3 secured to and connecting the intermediate portions of said bars. The ends of the platform are provided with recesses 4 and the bars 2 are made with recesses 5 at respective sides of the platform for purposes which will be hereinafter explained.

A frame 6 is located upon the bars 2 and is prevented from lateral displacement thereon by means of lugs 7 upon said bars. Longitudinal displacement of the frame 6 will be prevented by the engagement of said lugs with flanges 8 which project outwardly from plates 9 secured to the sides of frame 6, and the upper ends of these plates are provided with hooks 10.

The platform 3 constitutes a temporary bottom for the frame 6. At one end of the frame 6 a movable bar 11 is located and provided on its inner face with a series of lugs or blocks 12 which project into the recesses 4 in the adjacent end of the platform 3. The outer face of the bar 11 is inclined or beveled and coöperating therewith, is a wedge bar or block 13. The adjacent end of the frame 6 is provided with a slot 14 through which a pin 15, secured to the movable wedge-block passes. This pin is connected, by means of a rod or link 16, with an operating lever 17 mounted loosely upon a rod 18 passing through and rotatable in one of the side members of the frame 6. A rod 19 is similarly mounted in and extends through the other side of the frame 6. The bar 11 is provided near its ends with holes for the passage of the rods 18 and 19 and springs 20 located on said rods, bear at their respective ends against the bar 11 and lugs within the side members of the frame 6. The movements of the wedge-block 13 are guided by means of pins 21 projecting from the bar 11 and entering slots 22 in said wedge-block. When the lever 17 is moved in one direction the wedge-block 13 will be slid longitudinally and operate to move the bar 11 inwardly 110 against the resistance of the springs 20 and clamp a series of blocks or bricks between

said bar 11 and the lugs or blocks 12 thereon and a series of lugs or blocks 23—24 carried by the opposite end member of the frame 6. To lock the parts in the position just described the operating lever 17 is provided with a detent 25 to engage a toothed segment 26 secured to the frame 6. The lugs or block 23 are made of greater length than the lugs or blocks 24; alternate with the latter 10 and project into the notches 4 at the adjacent end of the platform 3. The lugs or blocks 23—24 are provided with sockets to receive pins 27 located within one end member of the frame 6 and behind each lug or block 23—24, a spring 28 is located. From this construction and arrangement of parts it will be seen that when a tier of bricks or blocks located upon the platform 3 is clamped longitudinally between the ends of the frame 20 6, one end of each row of bricks or blocks will engage a yielding lug or block (23 or 24) at one end of the frame and the other end of each row will be engaged by the bar 11 or one of the lugs 12 on the latter. The end bricks or blocks of the rows which engage the bar 11 at one end will engage the shorter yielding blocks 23 at the opposite end of the frame while the alternate rows of bricks or blocks will be clamped between the lugs 12 25 and the longer yielding blocks 24, thus causing the bricks of one row to break-joint with the bricks of the adjacent row.

The yielding blocks 23—24 are maintained in a proper upright position by means of pins 35 29 entering slots 30 in said yielding blocks.

In order to clamp a tier of bricks transversely or sidewise within the frame 6, clamping bars or members 31 are hinged to the respective side members of said frame 6 and 40 these clamping members 31 are moved inwardly to clamp the bricks in place by means of cams or lugs 32 secured to the rods or shafts 18 and 19. Each rod or shaft, 18 and 19, is provided with a crank-arm 33 and the 45 crank arms on the respective rods are connected by means of a rod 34. A rod 35 is pivotally connected at one end to the operating lever 17 and at the other end, said rod 35 is adapted for removable connection with 50 one end of the rod 34. From this construction, it will be seen that when the rod 35 is connected with the rod 34 and the operating lever 17 is operated, the wedge block 13 will be moved to effect the clamping of the bricks 55 longitudinally and at the same time, the shafts 18 and 19 will be partially rotated to cause their cams to engage the clamping members 31 and move the latter to clamp the bricks transversely within the frame 6. 60 Should it be desired to clamp the bricks end-wise only, the connecting rod 35 will be disconnected from the rod 34. When a tier of bricks shall have been clamped within the frame 6 the latter will be removed from the 65 base 1 and conveyed to the road-bed where

the bricks are to be deposited and when in proper position over the road-bed the lever 17 will be operated to release the tier of bricks and permit them to descend upon the road-bed. To properly guide the bricks as 70 they drop from the frame 6 to the road-bed, said frame 6 is provided at its sides and ends with depending guide-plates 36. For the same purpose the lugs 12 at one end of the frame and the lugs or blocks 24 at the other 75 end of the frame are provided with depending guide fingers 37.

My improvements not only permit the proper placing of bricks or blocks in position on a road-bed, but also facilitate the conveying of the same from a car, wagon or other source of supply. For the purpose of handling the device, both in depositing a tier of bricks on a road-bed and for conveying the device, a suitable crane may be employed 80 and connected by any desired means with the hooks 10. To increase the capacity of the device, both in depositing a tier of bricks on a road-bed and for conveying the device, a box or auxiliary frame 42 may be located upon the frame 6 and provided with arms or lugs 38 to engage projections 39 90 on the frame 6 to prevent displacement of said auxiliary frame. In loading the device the frame 6 is placed upon the bed-frame and a tier of bricks is placed in position on the platform 3 and clamped within the frame 6 in 95 the manner hereinbefore described. The auxiliary frame may now be placed in position on the frame 6 and several tiers of bricks arranged therein. The whole may then be conveyed to position over the road-bed and 100 the tier of bricks clamped within the frame 6 deposited upon the latter. The bottom tier of bricks in the auxiliary frame will then drop into position within the frame 6 and after having been clamped in the latter, the device 105 can then be moved to a new position over the road-bed and this tier of bricks deposited upon the latter in the same manner as before. These operations will be repeated until all the 110 tiers of bricks contained in the auxiliary frame shall have been deposited in position on the road-bed. The frame 6 with the auxiliary frame thereon may now be returned to the car or other source of supply and placed upon the base frame 1 (which latter may be 115 retained permanently at the source of supply) and again supplied with several tiers of bricks as before.

Strips 40 of asphalt or tar paper will preferably be placed between the bricks when the latter are placed in the frame, so that a more solid arch of brick will be formed. A sheathing 41 of tar or asphalt paper will also preferably be placed on the road-bed for the purpose of preventing the bricks from gathering 120 sand in case the bricks should have to be moved to their places, after the frame is lifted from them.

When the source of supply is some distance from the road-bed the apparatus may be con- 130

vveyed by means of a suitable wheeled device such as a truck.

Having fully described my invention what I claim as new and desire to secure by Letters-
5 Patent, is,—

1. In an apparatus for handling blocks or bricks, the combination with a frame, of means for clamping a series of blocks or bricks therein both transversely and longitudinally, and means for operating all of said clamping means simultaneously.
2. In apparatus of the character described, the combination with a frame, of means for clamping blocks or bricks therein transversely, means for clamping the blocks or bricks longitudinally of the frame, operating mechanism for each clamping means and means for detachably connecting said operating means.
3. In apparatus of the character described, the combination with a frame to receive blocks or bricks, of a clamping device at one end and yielding engaging devices for the blocks or bricks at the other end of the frame.
4. In apparatus of the character described, the combination with a frame to receive blocks or bricks, and side clamps, of an end clamp at one end of the frame, engaging means for blocks or bricks at the other end of the frame, means for operating the side clamps and the end clamps simultaneously.
5. In an apparatus of the character described, the combination of a frame to receive blocks or bricks, engaging means for the blocks or bricks at one end of the frame, a clamping device at the other end of the frame, a wedge-bar for operating said clamping device, and means for operating the wedge-bar.
6. In apparatus of the character described, the combination of a frame to receive blocks and bricks, engaging means for blocks or bricks at one end of the frame, a spring pressed clamping device at the other end of the frame, a wedge-block for operating said clamping device, and lever mechanism for operating the wedge-block.
7. In apparatus of the character described, the combination of a frame to receive blocks or bricks, engaging means for the blocks or bricks at one end of the frame, a spring pressed clamp at the other end of the frame, a slidable wedge-block for operating said clamp, an operating lever, a link connecting said operating lever with the wedge block, and means for locking the operating lever.
8. In apparatus of the character described, the combination of a frame to receive blocks or bricks, a series of yielding engaging devices at one end of the frame and a clamp at the other end of the frame.
9. In apparatus of the character described, the combination with a frame to receive blocks or bricks, of a series of spring pressed
- engaging devices at one end of the frame, 65 said engaging devices being alternately of different lengths, a clamping bar at the other end of the frame, lugs or blocks on said clamping bar and means for operating the clamping bar to clamp the blocks or bricks 70 between the same and the lugs thereon and the yielding engaging means at the other end of the frame.
10. In apparatus of the character de- 75 scribed, the combination of a frame to receive blocks or bricks, means for clamping the blocks or bricks in said frame, and guides depending from the side and end members of the frame.
11. In apparatus of the character de- 80 scribed, the combination with a frame to receive blocks or bricks and means for clamping the bricks and blocks in said frame, of an auxiliary frame disposed upon said first mentioned frame to receive superimposed tiers 85 of bricks or blocks.
12. In an apparatus of the character de- 90 scribed, the combination with a frame and engaging devices at respective ends of said frame, of guide-plates depending from the side and end members of the frame, and guide fingers depending from said engaging devices.
13. In apparatus of the character de- 95 scribed, the combination with a frame to receive blocks or bricks, of a clamping bar at one end of the frame, lugs projecting from said clamping bar, guide fingers depending from said lugs, engaging blocks at the other end of the frame, guide fingers depending 100 from said engaging blocks, shorter engaging blocks alternating with the first mentioned engaging blocks, and guide plates depending from the side and end members of the frame.
14. In apparatus of the character de- 105 scribed, the combination with a frame to receive blocks or bricks, of clamping bars attached to the side members of the frame, rods or shafts mounted in said side members of the frame and carrying lugs or cams to 110 engage said clamping bars, crank-arms on said rods or shafts, a rod connecting said crank-arms, a clamping device at one end of the frame, engaging means for blocks or bricks at the other end of the frame, a lever mounted 115 on one of said rods or shafts and connected with the clamping device at the end of the frame, and a rod connected at one end to said lever and removably connected at the other end with said first mentioned pitman. 120

In testimony whereof, I have signed this specification in the presence of two subscribing witnesses.

JAMES SHERIDAN.
